INVENTOR
FRED O. ANDERSON
BY
Andrew C. Carlson
ATTORNEY

UNITED STATES PATENT OFFICE

FRED O. ANDERSON, OF MINNEAPOLIS, MINNESOTA

BRUSH

Application filed February 23, 1929. Serial No. 342,215.

This invention relates to fountain brushes, particularly of the type that are adapted to be readily applied to a garden hose whereby water therefrom may be supplied to the brush when in use, and the primary object is to provide a brush of that character with an improved and efficient type of handle, whereby it may serve both as a handle for manipulating the hose and brush and simultaneously 10 acts as a gripping element to properly maintain the brush in an operative position with respect to and on the hose. Further and more detailed objects will be disclosed in the course of the following specification, reference being 15 had to the accompanying drawing, in which:

Fig. 1 is a plan view of a preferred or simplified form of the device.

Fig. 2 is a side elevation of the device as shown in Fig. 1.

Fig. 3 is a plan elevation of a modified form of the device with the brush proper omitted.

Referring to the drawing more particularly and by reference characters, A designates an ordinary garden hose to which a nozzle B is applied, and which may be adjusted to permit the water to be discharged either in a direct stream or in a spray, in a common and well known manner.

The brush unit embodying my invention 30 comprises a single wire, composed of two twisted strands, which wire is formed and shaped in a manner presently to be described. The brush element proper is formed by securing bristles between the wire strands, in a 35 substantially cylindrical coil, as illustrated, and this portion of the wire is then first bent into a U shape, which is then rebent, but at right angles to the first bend. As a result the brush element proper is bifurcated, in plan 40 view as seen in Fig. 1, with two arms 4 and 5; while the elevation illustrated in Fig. 2, discloses that the brush has an elongated hook effect by virtue of being bent back at the point 6. It will now also be seen that a crosssection (not 45 shown) through the brush will disclose four rectangularly spaced brush cores; and that these cores are so connected that the completed brush element can be pushed onto or pulled over an object to be cleaned. The 50 brush, it may here be noted, is particularly

designed for the purpose of cleaning motor cars, and the brush construction noted lends itself especially well for the purpose of cleaning wheels, spokes, bumpers, and other relatively narrow or small parts of the car. It may here also be noted that the brush element proper, while essentially a part of the present invention, is not described in detail or hereinafter claimed, *per se*, as it formed the subject matter of my Patent No. 1,575,809 issued on March 9, 1926, for Fountain brush.

The two brush forming wires, extend back from the bristle sections, in a pair of loops 7 and 8, the ends 9 being brought back and secured to intermediate portions 10 as by clips 11. The loops 7 and 8 are elongated, as shown, with arcuate ends 12, so as to fit snugly against the sides of the hose. It will be understood that there is sufficient flexibility in the entire wire to readily permit the spreading of the handle loops to detach the device, but that there is sufficient rigidity between the handle and brush, through the parts 9—11, to properly maintain the brush in the desired operative position with respect to the discharge end of the nozzle, if one is used on the hose.

It may here further be noted that the operator's hand may be the sole means of holding the handle loops 7 and 8 upon the hose, and that this is very practical in view of the fact that the same hand is simultaneously employed to grip and manipulate the hose, and that the brush can be so quickly and easily applied and removed as necessity may require.

It is sometimes desirable, however, to more permanently secure the device in place, and to this end I have provided a substantially rigid split ring 13, with an opening 14 through which the coil (7—8) wires may be successively passed by turning the ring from one position to another, to thus release or secure such wires within the embrace of the ring. This ring may have a spring or clamping action on the handles, although this is unnecessary.

In the modification shown in Fig. 3 the loops 7^a and 8^a are provided with complementing sections 15 that are so formed that

they will snap into place over the respective hose portions that they engage, it being understood that the sections 15 of each loop frictionally grip over more than one half of 5 the circumference of the adjacent hose portion.

It is understood that suitable modifications may be made in the structure as disclosed, provided such modifications come 10 within the spirit and scope of the appended claims. Having now therefore fully illustrated and described my invention what I claim to be new and desire to protect by Letters Patent is:

15 1. A fountain brush attachment for a hose comprising a brush member positioned in advance of the end of the hose to receive water therefrom, a pair of laterally disposed handle members extending rearwardly from 20 the brush member and for longitudinal contact with the sides of the hose to centrally grip the hose, and a split ring rotatable on the handle members for releasably securing them on the hose.

25 2. A fountain brush attachment for a hose comprising a brush member to be positioned in advance of the hose and having a pair of handle portions extending back for gripping engagement with opposite sides of 30 the hose, said handle portions each having a pair of parallel members connected at their ends by curved end portions.

35 3. A fountain brush attachment for a hose comprising a brush member to be positioned in advance of the hose and having a pair of handle portions extending back for gripping engagement with opposite sides of the hose, said handle portions each having a pair of parallel members connected at their ends by 40 curved end portions, and means for releasably securing the handle portions on the hose consisting of a rotatable split ring through the opening of which the said parallel members may be passed to secure and release the 45 handle portions with respect to the hose.

In testimony wherof I affix my signature.
FRED O. ANDERSON.
